UNITED STATES PATENT OFFICE

WILLIAM P. DAY, OF CLEVELAND HEIGHTS, OHIO

METHOD OF FORMING ROADBEDS FOR RAILWAYS

Application filed July 15, 1929. Serial No. 378,234.

This invention relates to a roadbed construction for railways and a method of forming the same. The main object of the invention is to provide a roadbed which will be 5 impervious to water and in which the concrete or other plastic material forming part of the roadbed is caused to bond with the rails in such a manner as to prevent cracks or crevices along the rails as a result of cars 10 passing thereover.

Another object of the invention is to provide a roadbed construction of the character described in which the rails, ties and concrete are bonded together and the concrete is 15 condensed and solidified so as to eliminate voids and provide a roadbed of maximum strength which will resist the vibration of the track due to heavy loads passing over the same and which will not permit water to seep 20 in adjacent the rails.

A still further object of the invention is to provide a roadbed construction and method of forming the same in which the track is vibrated while the concrete is still green or 25 soft to cause the same to thoroughly permeate the crushed stone and to bond with the rails and ties and substantially eliminate all voids.

Further and more limited objects of the 30 invention will appear as the description proceeds and by reference to the accompanying drawings in which Figs. 1, 2, 3, 4 and 5 are vertical sectional views through the roadbed illustrating the several steps in the method 35 of forming the same and Fig. 6 is a top plan view illustrating the type of tie used.

Heretofore it has been quite difficult and 40 practically impossible to obtain a roadbed construction for railways which will prevent water from seeping in along the rails. This has been due to the fact that the vibration of 45 the rails as a result of cars passing thereover has caused or produced crevices or cracks in which water may enter. The water deteriorates the roadbed material due to freezing

and thawing action and tends to enlarge the 50 crevices along the rails. According to my method of forming a roadbed, I have eliminated this difficulty by vibrating the rails while the concrete or other material forming the roadbed is still green or soft; and continuing this vibration until the concrete has 55 thoroughly permeated the stone and bonded with the rails and ties. The vibration of the rails also causes the concrete and stone to settle thus eliminating all voids between the 60 particles of stone and between the rails and the concrete and stone. Moreover, according to my method I am able to use from 5% to 15% more concrete in the same space and thus greatly increase the strength of the roadbed. Moreover, by eliminating these voids 65 between the steel and concrete and by providing a more perfect bond between the steel and concrete I greatly increase the structure's 70 ability to shed water and to resist vibration and therefore greatly prolong the life of the structure as a whole.

According to the preferred embodiment of 75 this invention, I first provide a trench which is slightly wider than the length of the standard tie and of such depth that the top of the rails will be disposed substantially level with the road surface. In this trench I arrange a plurality of blocks 1 and 2 which are 80 preferably formed of concrete and which may be of reinforced concrete, if desired. These blocks 1 and 2 are arranged in the trench in pairs, as disclosed most clearly in Fig. 6. I then place upon these blocks steel 85 ties of the twin type which are well known to those skilled in the art and as shown most clearly in Fig. 6. The tie consists essentially of rail plates 3 and 4 which are connected by angle bars or cross beams 5 and 6. After the ties are placed upon the blocks, 90 the rails 7, 8 are secured to the ties by means of tie clamps 9, 9^a and 10, 10^a in a manner well known to those skilled in the art. The trench is then filled with loose stone up to 95

about the level shown in Fig. 3. Soft concrete or grout is then deposited on the top of this layer of stone which is preferably delivered to the trench from a concrete mixer the 5 spout of which is indicated at 11 in Fig. 3 and which is moved forward at the rate of about one foot per minute. While the concrete is still green or plastic, and preferably simultaneously with the pouring operation, 10 the track is vibrated by means of a vibrator or pulsator which may be either mechanically or pneumatically operated and is preferably moved along the track from 10 to 25 feet behind the concrete mixer and at about the 15 same rate of speed as the concrete mixer.

In Fig. 3 I disclose one type of vibrator which consists essentially of a plate or bar on which are mounted hammers 13 and 14 adapted to be reciprocated to tamp or vibrate 20 the track. These hammers are preferably operated pneumatically although a mechanical vibrator may be used if desired. The number of blows of vibrations given to the track is preferably between 5200 and 6000 25 per minute. The vibrations of the track are transmitted through the ties with the result that substantially the whole mass of stone and concrete is subjected to the vibration and tends to settle and become more dense and by 30 the time that the concrete is thoroughly permeated through the stone, the whole mass will have assumed about the level shown in Fig. 4. As the vibrations of the track are imparted to the ties, the concrete tends to 35 flow along and between and against the rails and ties and to bond therewith. The vibrations of the rails also tend to substantially eliminate all voids in the mass and provide a structure which is exceedingly strong and 40 which will shed water. The vibration of the track is preferably simultaneous with the pouring of the concrete and the track is vibrated until there is no further settling of the stone and the concrete has thoroughly permeated the whole mass. The concrete will 45 bond with the rails and ties and there will be no cracks or crevices along the rails and hence there will be no chance of water seeping in along the rails. After the concrete 50 has hardened and set, further vibrations of the rails as a result of cars passing thereover will not destroy the bond between the concrete and rails or cause crevices along the rails. After the vibration has been continued for the proper length of time, the mass 55 will assume about the level shown in Fig. 4 and is allowed to harden and thoroughly set. The trench is then filled with a layer of surface material 15 which may consist of asphalt, concrete or any other suitable material. This upper layer of material is allowed to 60 harden and set and the roadbed is complete.

It is of course understood that various 65 changes may be made in the road forming

materials used and in the method of arranging the various parts in position as well as in the manner of delivering the concrete or other material and in the manner of vibrating the track, without departing from the 70 spirit of my invention.

In this specification I have used the term "concrete." However, by this term I do not wish to be limited to any specific mixture of sand, cement, stone or other material but have used the term generically to mean any mixture of a bonding material such as cement or asphalt with sand, gravel or stone or other material. It is therefore to be understood that the invention is limited only in accordance with the scope of the appended claims. It is also understood that my method is not limited to any particular type of tie or to a tie formed of any particular material, although a better bond is obtained when metal 80 ties are used.

Having thus described my invention, what I claim is:

1. The method of forming a roadbed for railways which consists in providing a trench of greater width than the track, arranging a plurality of steel ties within the trench with the rails secured thereto, said rails being disposed above the bottom of the trench, substantially filling the trench with loose stone, pouring soft concrete on the loose stone and vibrating the rails until the concrete thoroughly permeates the stone and bonds with the rails and ties. 90

2. The method of forming a roadbed for railways which consists in providing a trench of greater width than the track, arranging a plurality of steel ties within the trench with the rails secured thereto, said rails being disposed above the bottom of the trench, substantially filling the trench with loose stone, pouring soft concrete on the loose stone and vibrating the rails until the concrete thoroughly permeates the stone and bonds with the rails and ties and continuing such vibration until the mass thus formed has set. 100

3. The method of forming a roadbed for railways which consists in providing a trench of greater width than the track, arranging a plurality of steel ties within the trench with the rails secured thereto, said rails being disposed above the bottom of the trench, substantially filling the trench with loose stone, pouring soft concrete on the loose stone and vibrating the rails until the concrete thoroughly permeates the stone and bonds with the rails and ties and then filling the trench with a layer of road forming material. 115

4. The steps in the method of forming a 125 roadbed for railways which consist in providing a trench and laying the track therein, substantially filling the trench with loose particles of stone, pouring soft concrete on the loose stone and simultaneously vibrating 130.

the track until the soft concrete permeates the stone and bonds with the rails and ties.

5. The steps in the method of forming a roadbed for railways which consist in providing a trench and laying the track therein, substantially filling the trench with loose particles of stone, pouring soft concrete on the loose stone and simultaneously vibrating the track until the soft concrete permeates the 10 stone and bonds with the rails and ties and continuing such vibration until the mass thus formed has set.

6. The steps in the method of forming a roadbed for railways which consist in providing a trench and laying the track therein, substantially filling the trench with loose particles of stone, pouring soft concrete on the loose stone and simultaneously vibrating the 15 track until the soft concrete permeates the stone and bonds with the rails and ties and then filling the trench with a layer of road forming material.

7. The steps in the method of forming a roadbed for railways which consist in providing a trench and laying the track therein, substantially filling the trench with loose 25 particles of stone, pouring soft concrete on the loose stone and vibrating the track until the soft concrete permeates the stone and bonds with the rails and ties.

8. The steps in the method of forming a roadbed for railways which consist in providing a trench and laying the track therein, substantially filling the trench with loose 35 particles of stone, pouring soft concrete on the loose stone and vibrating the track until the soft concrete permeates the stone and bonds with the rails and ties and continuing such vibration until the mass thus formed has 40 set.

9. The steps in the method of forming a roadbed for railways which consist in providing a trench and laying the track therein, substantially filling the trench with loose 45 particles of stone, pouring soft concrete on the loose stone and vibrating the track until the soft concrete permeates the stone and bonds with the rails and ties and then filling the trench with a layer of road forming 50 material.

10. The method of forming a roadbed for railways which consists in laying the track and filling the space between and adjacent the rails with particles of stone, depositing 55 concrete on the layer of stone and vibrating the rails to cause the concrete to permeate the layer of stone.

11. The method of forming a roadbed for railways which consists in laying the track and filling the space between and adjacent the rails with particles of stone, depositing 60 concrete on the layer of stone and vibrating the rails to cause the concrete to permeate the layer of stone and continuing such vibration 65 until the concrete has set.

12. The method of forming a roadbed for railways which consists in laying the track and filling the space between and adjacent the rails with particles of stone; depositing concrete on the layer of stone and vibrating the 70 rails to cause the concrete to permeate the layer of stone and continuing such vibration until the concrete has thoroughly permeated the layer of stone and bonded with the rails.

13. The method of forming a roadbed for railways which consists in laying the track and filling the space between and adjacent the rails with particles of stone; depositing concrete on the layer of stone and vibrating the 75 rails to cause the concrete to permeate the layer of stone and continuing such vibration until the concrete has thoroughly permeated the layer of stone and bonded with the rails and allowing the mass thus formed to harden 80 and set and then applying a layer of surface material.

14. The method of forming a roadbed for railways which consists in providing a trench of greater width than the track, arranging a plurality of ties within the trench at intervals, securing the rails to the ties, filling the trench with particles of stone, depositing concrete on the layer of stone and vibrating the rails to cause the concrete to flow through the 90 stone.

15. The method of forming a roadbed for railways which consists in providing a trench of greater width than the track, arranging a plurality of ties within the trench at intervals, securing the rails to the ties, filling the trench with particles of stone, depositing concrete on the layer of stone and vibrating the rails to cause the concrete to flow through the stone and continuing such vibration until the concrete has thoroughly permeated the mass of 100 stone and bonded with the rails.

16. The method of forming a roadbed for railways which consists in providing a trench of greater width than the track, arranging a plurality of ties within the trench at intervals, securing the rails to the ties, filling the trench with particles of stone, depositing concrete on the layer of stone and vibrating the rails to cause the concrete to flow through the stone and continuing such vibration until the concrete has thoroughly permeated the stone.

17. The method of forming a roadbed for railways which consists in providing a trench of greater width than the track, arranging a plurality of ties within the trench at intervals, securing the rails to the ties, filling the trench with particles of stone, depositing concrete on the layer of stone and vibrating the rails to cause the concrete to flow through the stone and continuing such vibration until the concrete has thoroughly permeated the stone and bonded with the rails.

18. The method of forming a roadbed for railways which consists in providing a trench of greater width than the track, arranging a 125

plurality of metal ties within the trench at intervals, securing the rails to the ties, filling the trench with particles of stone, depositing concrete on the layer of stone and vibrating the rails to cause the concrete to flow through the stone and continuing such vibration until the concrete has substantially filled all voids in the stone and bonded with the rails and ties.

10 In testimony whereof, I hereunto affix my signature.
